INFANT'S TOILET SEAT

Dale P. Smith, Jr., Huntington Park, Calif.

Application October 19, 1950, Serial No. 191,019

2 Claims. (Cl. 4—239)

1

This invention relates to toilet seats for infants and deals more particularly with the type that are attached to toilets for adult use.

Prior devices of this nature had a major fault in that separate manipulation of the infant's seat was necessary to give access to the adult's seat. Most toilets are provided with a lid that covers the seat opening and the same is, of course, raised. In the mentioned earlier devices, it is necessary to raise both the lid and the infant's seat separately.

It is an object of the present invention to so combine an infant's seat and the lid of a toilet that the lid alone or both the lid and said seat can be raised, as desired.

Another object of the invention is to so combine the lid and infant's seat that both together, when the latter is folded, occupy the same space as the lid alone, thus providing a neat structure that outwardly has the appearance of a conventional lid.

Another object of the invention is to provide a novel infant's seat that folds to a flat condition of such small thickness that the same resides entirely within a seat or cavity formed in the lid and is flush with the under face of said lid.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a longitudinal sectional view of a toilet seat structure according to the present invention.

Fig. 2 is a bottom plan and sectional view as taken on line 2—2 of Fig. 1, and viewed in the direction of the arrows.

Fig. 3 is an enlarged, partly broken, side view of the seat in an intermediate position between fully folded and fully opened positions.

In a conventional manner, the bowl 5 is provided with an adult's seat 6 and with a lid or cover 7 to cover the opening of said seat. A pivot bar 8 at the rear of the bowl and supported by standards 9, pivotally mounts the seat and lid

2

so that the lid alone or the lid and seat may be swung upwardly to an erect position. While otherwise conventional, the lid 7, according to the present invention, is provided with a cavity 10 that faces downwardly when said lid is down. A folding infant's seat 11 is housed within said cavity, is separately connected to pivot bar 8 by means of an extension 12, and is retained in said cavity by means of a releasable latch 13. It will be clear that, when latched together, the lid 7 and folded seat 11 moves together on bar 8 in the same manner as if the lid did not house an infant's seat, since the same move on a common pivot axis.

15 The seat 11 comprises, generally, a seat board 14, a seat back 15, and side arms 16. The board and back are connected by aligned hinges 17.

The seat board 14 is shaped substantially in accordance with the shape of cavity 10 to freely fit thereto and to have its under face 18 generally flush with the under face 19 of lid 7. A central ovate opening 20 is formed in seat board 18, the same being smaller than and substantially centered with the comparable opening 21 of seat 6.

25 The seat back 15 is formed to have a panel part 22 approximately the width of the seat board, and a thickened back pad 23 that is shaped to freely fit into ovate opening 20, the same completing the flush appearance of the under face of the structure. It will be seen that in the closed or folded condition of Fig. 1, the seat back 15 is superposed on seat board 14 on the inner side of cavity 10 and that hinges 17 are on the same side and, therefore, concealed by the seat board.

30 Each side arm 16 comprises an arm rest 24 that is connected by a pivot 25 to an edge of seat back panel 22, and a brace 26 pivoted at 27 to the seat board and at 28 to the arm rest. The latter 40 comprises a part 29 which is carried by pivot 25 and is provided with an end socket 30 to telescopically receive and guide an arm rest extension 31. The pivot 28 is provided in said extension. A pin-and-slot connection 32 slidably connects extension 31 and arm rest part 29.

45 It will be noted from Fig. 2 that the side edges of back panel 22 are notched, as at 33, to accommodate arm rest parts 29 whereby the latter are enabled to lie, for the most part, within the side peripheral edges of the seat board 18 and against the upper face of said seat board, the sum of the thicknesses of the seat board and arm rest part 29 being equal to the depth of cavity 10 to achieve the mentioned flush condition of the lid and the seat board.

55 The braces 26 are arranged alongside the side

edges of the seat board and are so formed as not to laterally overhang arm rest parts 26. The end of each brace at pivots 28 reside in slots provided in arm extensions 31, as indicated in Fig. 3. To allow flat folding of the seat, a recess 34 is formed in each arm rest part 29 to accommodate the bearings 35 on board 18 that carry pivots 27.

It will be clear that when lid 7 is raised to the dot-dash line position of Fig. 1, seat 11 will be similarly raised. However, upon depression of latch 13 to release engagement with the seat, the lid alone will be raised leaving the folded seat 11 superposed on seat 6. Now the seat back 15 may be raised on its hinges 17 to effect unfolding of the folded arm rests 16. By providing abutments 36 (Fig. 3), the erect position of the seat back is limited to a suitable slightly rearward angle as shown by the dot-dash lines of Fig. 1. An abutment shoulder 37 on each end of braces 26 limits the unfolding movement of said braces. The pin-and-slot connections 32 limit the telescopic extension of arm rests 16 so that a rigid open condition of the seat 11 is achieved wherein seat back 15 may be swung through a greater arc of movement than braces 26. Thus, by a simple upward-swinging movement of the seat back, the seat 11 is unfolded. The seat is as easily folded by pushing down on the seat back.

The latch 13 may be depressed by one finger of the hand that raises lid 7 and said latch may automatically engage the end of seat board 18 when the lid is dropped.

To enable removal of seat 11 for use elsewhere, the extension 12 is formed of separable parts 38 and 39 that are releasably connected as by a turn-bolt 40. As shown, part 38 is fixedly connected to seat board 18 while part 39 has hooking engagement at 41 with part 38. The turn-bolt 40 is carried by part 38 and extends through a slot 42 provided in part 38. The parts are locked when the head of the turn-bolt stands transverse to slot 42, as shown. When said head is turned to align with said slot, parts 38 and 39 may be separated to effect their removal from pivot bar 8.

While the invention that has been illustrated and described is now regarded as the preferred embodiment, the construction is, of course, subject to modifications without departing from the spirit and scope of the invention. It is, therefore, not desired to restrict the invention to the particular form of construction illustrated and described, but to cover all modifications that may fall within the scope of the appended claims.

Having thus described the invention, what is claimed and desired to be secured by Letters Patent is:

1. In a toilet seat structure, a lid having a

downwardly facing cavity, a folded seat residing within said cavity, hinges for said lid and seat on a common axis and said axis being disposed rearward of the lid and seat, said lid having an opening therethrough adjacent the forward end thereof, and a latch carried by the lid in latching engagement with the seat and provided with an operating member extending through said opening and accessible from the upper side of the lid, said folded seat comprising a seat board secured to said seat hinge, a seat back hinged to the rearward portion of said seat board, a pair of braces pivoted to the forward portion of said seat board on opposite sides thereof and a pair of arm rests each having one end thereof pivotally connected to said seat back and the other end pivotally connected to one of said braces, each of said arm rests being comprised of two members slidably longitudinally of each other so that said folded seat can be horizontally within said cavity and can be extended to place said seat back in substantially vertical position and said arm rests in substantially horizontal position above said seat board.

2. In a toilet seat structure, a lid having a downwardly facing cavity, a folded seat residing within said cavity, hinges for said lid and seat on a common axis and said axis being disposed rearward of the lid and seat, said folded seat comprising a seat board secured to said seat hinge, a seat back hinged to the rearward portion of said seat board, a pair of braces pivoted to the forward portion of said seat board on opposite sides thereof and a pair of arm rests each having one end thereof pivotally connected to said seat back and the other end pivotally connected to one of said braces, each of said arm rests being comprised of two members slidably longitudinally of each other so that said folded seat can be horizontally within said cavity and can be extended to place said seat back in substantially vertical position and said arm rests in substantially horizontal position above said seat board.
